UNITED STATES PATENT OFFICE.

CHARLES W. GRIFFIN, OF RIEGELSVILLE, NEW JERSEY.

WASTE-PAPER SHREDDER.

Application filed September 20, 1923. Serial No. 663,832.

To all whom it may concern:

Be it known that I, CHARLES W. GRIFFIN, a citizen of the United States of America, and a resident of Riegelsville, in the county of Warren and State of New Jersey, have invented a new and useful Waste-Paper Shredder, of which the following is a specification.

My invention relates to improvements in machines for cutting or shredding waste material such as paper and rags, and consists essentially of a knife cylinder or head, shaft, and balance-wheel all in one piece, a knife bed provided with a discharge trough, and certain peculiar blades or knives for said head, together with such other parts and members, in combination with those mentioned above, as may be necessary or desirable in order to render the machine complete and serviceable in every respect, all as hereinafter set forth.

The primary object of my invention is to produce a small, compact, strong, and durable machine which is capable of efficiently shredding waste material, and more especially waste paper for use as packing.

Another object is to provide such a machine with reversible knives for the revolving head, and means whereby such knives can be readily attached to and detached from said head and reversed thereon.

A further object is to furnish the machine with a bed having an integral trough which renders it unnecessary to provide an apron or other separate device for removing the cut material from beneath or within the machine, inasmuch as said bed prevents the stock from dropping down under the knives, and also supports said stock so near the revolving knives that they throw it out of the machine through said trough.

This machine or shredder is comparatively inexpensive to construct and operate, and the knives of the same can be changed and adjusted easily and quickly.

Other objects and advantages will appear in the course of the following description.

I attain the objects and secure the advantages of my invention by the mechanism illustrated in the accompanying drawings, in which—

Figure 1 is a side elevation of a shredder which embodies a practical form of my invention; Fig. 2, a side elevation and top plan, respectively, of an end portion of the

feed roll and the supporting terminal of one of the arms that carry said roll; Fig. 3, a vertical, longitudinal section through the upper part of said shredder; Fig. 4, a reduced top plan of the bed, and, Fig. 5, a side elevation of the knife cylinder or cutting head and integral trunnions and enlargements.

Similar reference characters designate similar parts throughout the several views.

The shredder comprises a frame 1 of any suitable or approved construction, and a superimposed bed 2 and pair of brackets 3. Journaled in suitable bearings in the lower part of the frame 1 is a transverse shaft 4, and secured to said shaft, at opposite ends outside of said frame, are pulleys 5 and 6 respectively, the former being larger than the latter. The brackets 3 are bolted at 7 to the top of the frame adjacent to the rear edge thereof, said brackets extending rearwardly and upwardly to form bearings at their free ends for a transverse shaft 8. Secured to the shaft 8, at opposite ends thereof and outside of the brackets 3, are a sprocket-wheel 9 and a pulley 10, respectively. A belt 11 connects the pulley 6 with the pulley 10. A feed box 12 has a pair of lugs 13 bolted to the under side thereof, which lugs are loosely mounted on the shaft 8 inside of the brackets 3. The box 12 extends forwardly above the rear portion of the bed 2, and rests by gravity on a bed-knife 26 adjacent to the front edge thereof. Also loosely mounted on the shaft 8, between the brackets 3 and the lugs 13, are two forwardly-extending and upwardly-inclining arms 14 which afford bearings at their front terminals for a feed-roll shaft 15. Secured to the shaft 15 are a feed-roll 16 and a sprocket-wheel 17. The sprocket-wheel 17 is outside of the feed box and in front of the sprocket-wheel 9, and a sprocket-chain 18 connects said sprocket-wheels.

The feed-roll 16 is provided at each end with a disc or annular flange 19, and its teeth or feeding members are in the form of a series of ribs 20. The ribs 20 extend between the flanges 19, and are equidistant apart and parallel with the axis of the feed-roll 16. The length of the feed-roll is approximately equal to the width of the feed box 12 between the sides thereof, and said feed-roll normally is located by the arms 14 with the lower portion of the roll between

said sides. The forward terminal portions of the sides of the box 12 are cut down to receive on the upper edges thereof hubs which extend inwardly from the arms 14 at their forward ends, it being such hubs that form the bearings for the shaft 15. One of the aforesaid hubs is shown in full lines in Fig. 2, and indicated by dotted lines in Fig. 3 at 21. The feed-roll is supported by the means 10 and in the manner just described with the ribs 20 out of contact with the bottom of the feed box.

The parts and members thus far described are generally or in the main old and well known.

The bed 2 has outwardly-extending lugs 22-22 on each side thereof, and each of said lugs is bolted at 23 to the top of the frame 1. Extending across the bed 2 at the rear end is a raised part or flange 24, and forward of such part is a horizontal support 25 for the bed-knife 26. The bed 2 is hollowed out between the sides thereof in front of the support 25 to form a trough, the 25 sides of said trough being vertical and parallel, and the bottom of said trough curving downwardly from said support to form a concave part 52, and extending forwardly and downwardly from said curved part to 30 form a tangential, straight, and unbroken part 53 having a downward pitch. Extending laterally from the sides of the bed 2 are two bearings 27. A bearing cap 28 is provided for each of the bearings 27, and 35 is adapted to be bolted thereto at 29-29. The bed 2, including the lugs 22, flange 24, support 25, trough (52 and 53), and bearings 27, is all made in one piece, which renders the same comparatively inexpensive 40 and easy to assemble with the other parts of the machine.

That portion of the bed 2 which comprises the flange 24 and the support 25 is higher than that portion of said bed which comprises the trough (52 and 53), and both of such portions are above the bottom edges 45 of the sides of the bed.

There are two (more or less) vertical slots 30 in the support 25 of the bed 2, and the 50 same number (more or less) of horizontal passages 31 in the flange 24 of said bed. A pair of adjusting set-screws 32 are received in the passages 31, and mounted on said set-screws on opposite sides of the flange 55 24 are two pairs of nuts 33. The nuts 33 in the front pair are received in recesses 34 in the front side of the flange 24, so that said nuts are prevented from turning with the set-screws 32.

60 The bed knife 26 is double edged, that is to say, both longitudinal edges thereof are cutting edges, and there are countersunk holes in said knife to register with the slots 30, one of which holes appears at 35 in Fig. 3. A lock bolt 36 passes down through

each hole 35 and the slot 30 below to receive a nut 37 beneath the support 25, the head of said bolt being countersunk in the bed-knife 26. The set-screws 32 are in position to receive against their inner ends the back edge of the bed-knife 26. By means of the two vertical bolts (36) and nuts (37) and the set-screws 32 and nuts 33, the bed-knife 26 is secured to the support 25, with the front edge of said knife 75 extending over the front edge of said support in cutting position. It is necessary, of course, to loosen the rear nuts 33 before turning the set-screws 32 for the adjustment of the bed-knife, and to retighten said nuts after such adjustment. The nut 37 on each bolt 36 is tightened after the proper adjustment of the bed-knife has been made by means or through the medium of the set-screws. The heads of the set-screws 32 and the rear nuts 33 are easily accessible, likewise each nut 37, the latter being located in the space beneath the support 25 and between the sides of the bed 2, which space opens behind. In order to remove and replace the bed-knife, it is first necessary to swing the feed box 12 with the feed-roll 16 upwardly on the shaft 8.

The bed-knife and adjusting and securing members therefor are old.

Provided to cooperate with the bed-knife 26 are two knives 38 which are secured on diametrically opposite sides of a revolving head 39. Extending from one end of the head 39 is a trunnion 40 having at its outer end an enlargement 41 to receive a driving pulley 42; and at the other end of said head is a trunnion 43 having at its outer end an enlargement 44 to form a fly-wheel. The head 39 and the trunnions 40 and 43 105 with their enlargements are all made in one piece. The trunnions 40 and 43 are received in the bearings 27 and held therein by means of the caps 28 and bolts 29. The trunnion 40 extends outwardly beyond its bearing over the pulley 5, and a belt 45 connects said trunnion with said pulley.

Opposite sides of the head 39 are flattened to form parallel beds or supports 46-46 for the knives 38, and said head has a plurality of passages 47 formed therein, which passages open at opposite ends through said supports. In the present case there are eight passages 47 arranged in pairs side by side and equidistant apart, the passages 115 in each pair being equidistant from the diameter of the head 39 which is at right-angles to the supports 36. The passages 47 are adapted to receive bolts 48, and one end of one passage and the opposite end of the other passage in each pair are enlarged to enable the heads of the bolts in said passages to be countersunk, such bolts being inserted from opposite directions. Each bolt 48 is of sufficient length to pass through 120

the head 39 and one of the knives 38, and to receive a nut 49 thereon outside of said knife. Each knife 38 has two oppositely-disposed cutting edges, is recessed in its outer 5 side, as at 50, to receive the engaging nuts 49 and locate such nuts in part within the superficial outer surface of said knife, and has therein four, laterally-extending, equidistant slots 51 to receive the same number of bolts 10 48 and permit of the lateral adjustment of the knife on said bolts. Each knife 38 is placed in position on one of the beds 46, with the terminals of the four bolts which project beyond said bed in the slots 51 of 15 said knife, the nuts 49 for said bolts are screwed onto the same, said knife is adjusted on said bed so that the leading cutting edge of the same, in the direction of rotation of the head 39, just clears the front cutting edge of the bed-knife 26, and said nuts are tightened. Each knife 38 covers the heads of four of the bolts 48, and receives in its recess 50 the nuts 49 on the 20 other four bolts 48.

25 The curved part 52 of the bottom of the aforesaid trough is concentric with the head 39, and the part 53 of said bottom extends forwardly beneath said head. The bottom parts 52 and 53 are also quite close to the 30 circular path of the leading cutting edges of the knives 38.

After the bed-knife 26 has been placed in position and adjusted, and the knives 38 have been secured to the head 39 in proper 35 positions relative to said bed-knife, the machine is set in motion and operates in the following manner:

The pulley 42, which is driven from a countershaft having a belt (not shown), rotates the trunnion 40 and the head 39, with 40 the knives 38 thereon, in the direction of the associated arrow in Fig. 3, the trunnion 43 and fly-wheel 44 revolving with the other members, said first-named trunnion, through 45 the medium of the belt 45 and the pulley 5, causes the shaft 4 to revolve, said shaft, through the medium of the pulley 6, the belt 11, and the pulley 10, causes the shaft 8 to 50 revolve, and the latter, through the medium of the sprocket-wheel 9, the sprocket-chain 18, and the sprocket-wheel 17, causes the shaft 15 with the feed-roll 16 to revolve in the direction of the associated arrow. The 55 stock to be cut is placed in the feed box 12, and the feed-roll 16 actuates or moves said stock forwardly out of the front end of said box over the bed-knife 26, where said stock is cut or shredded by the knives 38 on the head 39, which latter is revolved at 60 a sufficiently high rate of speed for the purpose. The stock as it is shredded drops down into the trough (52 and 53) and is swept or carried forward in said trough and out through the front end thereof by the 65 impetus imparted thereto by the revolving

knives. Thus the shredded stock is thrown clear of the machine into any suitable receptacle which may be provided to receive the same.

While the head 39 is revolved at a comparatively high rate of speed, the feed-roll 16 is revolved at a comparatively low rate of speed, as is necessary in a machine of this character. The slow speed of the feed-roll 16 is due to the means introduced for stepping down the transmission between the trunnion 40 to said feed-roll.

After the cutting edge of either knife 38 becomes dull, said knife is reversed to locate the other cutting edge in operative position, which is a decided advantage, as will be readily understood.

Much saving in expense and labor result from the integral construction of the head 39, trunnions 40 and 43, enlargement 41, and fly wheel 44, as in the case of the bed 2, and such construction is especially desirable and entirely practicable in a small machine.

More or less change in the shape, size, construction, and arrangement of some or all of the parts of this shredder may be made without departing from the spirit of my invention, or exceeding the scope of what is claimed.

What I claim as my invention, and desire to secure by Letters Patent, is—

1. The combination, in a shredder, with a revoluble knife-head, of a bed-knife support having an open-top and open-end integral trough with its bottom beneath said head, and consisting of a part which is approximately concentric with said head, and of a part which is straight and unbroken, tangential to said first-named part, and has a downward pitch.

2. The combination, in a shredder, with a revoluble knife-head provided with axial supporting members, of a bed-knife support having an open-top and open-end integral trough with its bottom beneath said head, and consisting of a part which is approximately concentric with said head, and of a part which is straight and unbroken, tangential to said first-named part, and has a downward pitch, the sides of said trough affording bearings for said axial supporting members, and positioning said head over said bottom.

3. In a shredder, a bed-knife support having at the rear edge an upstanding flange for adjusting means for the bed-knife, and having forwardly-extending sides and a downwardly- and forwardly-extending bottom to form an open-top and open-end trough, said bottom consisting of a curved part and of a straight and unbroken part tangential to said curved part, and all of such parts and members being integral.

4. In a shredder, a bed-knife support having at the rear edge an upstanding flange

for adjusting means for the bed-knife, and having forwardly-extending sides and a downwardly- and forwardly-extending bottom to form an open-top and open-end trough, said bottom consisting of a curved part and of a straight unbroken part tangential to said curved part, said sides having laterally-extending bearings, and all of such parts and members being integral.

CHARLES W. GRIFFIN.
